UNITED STATES PATENT OFFICE.

JOHN B. OWENS, OF METUCHEN, NEW JERSEY.

METHOD AND MEANS FOR FIRING TUNNEL-KILNS.

1,355,906.

Specification of Letters Patent. Patented Oct. 19, 1920.

Application filed August 24, 1918. Serial No. 261,282.

To all whom it may concern:

Be it known that I, JOHN B. OWENS, a citizen of the United States, residing at Metuchen, in the county of Middlesex and State of New Jersey, have invented certain new and useful Improvements in Method and Means for Firing Tunnel-Kilns, of which the following is a specification.

The present invention has for its object 10 the provision of a new method of firing a tunnel kiln and the construction and arrangement of a combustion chamber and arch whereby said method may be practised.

The invention contemplates, first, substantially complete combustion of the fuel prior 15 to entry of the burned gasses into the tunnel and on, and around, the goods in the latter, thereby producing an oxidizing fire and minimizing blackening, specking, or otherwise discoloring or damaging the goods or wares in the tunnel; second, a novel manner 20 of dissemination of the heat derived from combustion, including assistance in combustion, to the end that the heat delivered or directed to the goods or wares in the tunnel is obtained at a great saving in the fuel consumed, and is directed downwardly so that 25 it will play more heavily on the lower portions of the stacks of ware on the cars than on the upper portions of said stacks and thereby so direct the heat that the draft will cause it to naturally rise and disseminate 30 throughout the ware on the cars, thus insuring an even firing of the ware contained in all of the saggars, or, whatever containers may be used on the cars for holding the 35 ware.

My invention is carried out, first, by the provision of a firing or combustion chamber or furnace which extends alongside the tunnel, preferably parallel thereto, and is fired in the direction of its length, that is lengthwise of the tunnel, either from one or both ends, but preferably from the end nearest the exit end of the tunnel. This method of firing and arrangement of combustion chamber not only insures substantially complete combustion of the fuel prior to the heat units passing to the goods or wares in the tunnel but it also prevents blackening, specking, or otherwise discoloring the goods which the delivery of unconsumed heat units to the goods would bring about.

My invention is carried out, in the sec-

ond place, by the provision of an arch extending in general transverse relationship to the tunnel and the combustion chamber or chambers, which constitutes the top of the combustion chamber or chambers and of the tunnel. This arch is preferably of semi-circular form and, in connection with the combustion chamber or chambers (there being preferably two combustion chambers, located on opposite sides of the tunnel), it not only assists in effecting combustion within the chamber or chambers, but also radiates its heat toward the ware or goods contained within the tunnel, thereby most effectively disseminating the heat from the consumed gases through the ware or goods and effecting a great saving in the amount of fuel required.

The arch may be insulated in any manner desired to prevent loss of heat upwardly and outwardly therefrom so as to insure the internal radiation above referred to.

It is within the spirit of my invention as regards the arch, to employ a plurality, say two, of smaller arches instead of a single, substantially semi-circular arch but the single arrangement is preferred. Such an arrangement might be sufficiently wide or large to permit the use of a two-track tunnel, there being a partition between the two, parallel, tunnels outside of the burning zone of the tunnel.

My invention is carried out, third, by baffling the heat and products of combustion as they pass from the combustion chamber so that they will be directed downwardly as they flow from the combustion chamber and thus initially play more heavily on the lower portions of the stacks of ware on the cars, thence rising upwardly and disseminating throughout the ware due to the draft of the kiln, insuring even firing of the ware at all heights of the stack thereof.

The invention is susceptible of modification without departing from its essential features of construction and mode of operation in firing the goods or ware. The constructions shown and described, are, therefore, to be considered as susceptible of modification within the scope of the invention.

In the accompanying drawings:

Figure 1, is a horizontal section through the two combustion chambers and a portion of the burning zone of a tunnel kiln embodying my invention, the tunnel being

broken away at both ends of the combustion chambers;

Fig. 2 is a vertical cross-section on line 2—2, Fig. 1;

5 Fig. 3 is a longitudinal section on line 3—3, Fig. 2; and

Fig. 4 is a vertical cross-section, showing an embodiment of the invention according to the disclosures of my Patent No. 1,288,975, 10 dated December 24, 1918.

While my invention is particularly adapted for use with the "Owens" type of tunnel kiln, it may be employed in connection with any tunnel kiln.

15 In the drawings I have shown only a portion of the burning or firing zone of a tunnel kiln at 1, having tracks 2 for the cars which convey the goods or wares through the tunnel from the entrance to the exit thereof.

20 The preheating and cooling zones of the tunnel are omitted.

Referring first to Figs. 1 to 3, the combustion chambers are preferably located on opposite sides of the tunnel. These chambers extend alongside the tunnel on opposite sides of the firing or burning zone 1 and communicate with the firing zone by openings 4. The combustion chambers 3 are fired from either or both ends thereof in 30 the direction of their lengths and, preferably, from their ends which are nearest to the exit end of the tunnel.

In the drawings I have shown openings 5, 6 to admit either oil or gaseous fuel burners at that end of the combustion chamber which is nearest the exit end of the tunnel. Such fuel means could be located at the other end of the combustion chamber, or, at both ends thereof. Coal could be employed at the points indicated, instead of either oil or gas, as the firing medium. In any instance, the combustion chamber is fired in the direction of its length, that is, substantially parallel to the firing zone 1 of the tunnel. The purpose of this method of firing is to insure substantially complete combustion of the fuel within the combustion chamber and to consume the gases before they enter the firing zone 1 through 50 the opening 4, in each instance. An oxidizing fire is thus obtained and danger of specking, blackening, or otherwise discoloring the ware or goods in the tunnel entirely eliminated.

55 In my application, Serial No. 144,071, filed January 23, 1917, I have disclosed and claimed combustion chambers which are fired in the direction of their length, and the method of firing said combustion chambers.

A single, large arch 7 constitutes the outermost sides and the tops of the combustion chambers 3 and, also the top of the firing or burning zone 1, said arch extending transversely of the kiln where the com-

bustion chambers are located and being of the same length as said chambers. This arch may be suitably insulated, as by the use of "cork brick," asbestos, keisenguir earth, or other means, to prevent loss of heat by 70 radiation outwardly and upwardly from the arch. I do not consider such insulation essential, although it is preferable, to obtain increased thermal effects. Preferably the arch 7 is substantially semi-circular, rising 75 from the outermost parts of the benches 8 and crowning the combustion chambers and the tunnel. The arch has a two-fold function: first, it assists combustion in the chambers 3 in connection with the lengthwise firing in said chambers, as previously explained; second, it radiates heat toward the goods or wares on the cars in the tunnel, thus insuring that they be subjected to a maximum number of heat units with the 85 consumption of a minimum amount of fuel.

Baffles 9, depending from the arch 7 in line with the inner walls of the benches 8, may be used to assist the combustion within the chambers 3 and to deflect the heat downwardly toward the bottom of the goods or ware on the cars as it issues through the openings 4 into the burning or firing zone 1. In other words, the heat from the combustion chambers 3 is forced in and around 95 the ware 5 just over the top of the car platform 4 and naturally rises and disseminates throughout the ware thereupon. The result is that the ware above the bottom of the stacks is burned at substantially the 100 same temperature as the ware at the middle and top of each stack and a uniform firing of the ware is obtained.

The construction shown in Fig. 4 is an embodiment of the invention according to 105 the disclosures of my Patent No. 1,288,975, dated December 4, 1918, and to that extent the present application is a continuation in part of said application.

This form of the invention is designed to 110 use producer gas as fuel for firing the ware. The fuel gas is supplied from a main, not shown, through ducts 35 to the mixing chambers 36, the walls of which are provided with air inlets 37 which may communicate 115 directly with the outer atmosphere, or they may be connected by ducts, not shown, with a source of supply of preheated air. The circulation through these ducts may be either induced or forced. The mixing chambers 36 are separated from the combustion chambers 39 by walls 40 having arched openings 41, said combustion chambers being separated from the interior of the furnace proper by walls 42 of checker-work made 120 of fire brick or other refractory material. The checker-brick serves to distribute the heat uniformly, and it also acts as an accumulator for holding or retaining the heat at a point where the highest temperature is 130

required. The checker-brick also acts as a mixer for the air and fuel gas, thereby promoting perfect combustion.

The mixing chambers and combustion chambers may be combined by eliminating the walls 40, whenever conditions may make this advisable, without affecting the principle of operation.

I claim as an advantage for the combustion chamber paralleling the tunnel of the kiln, that the heat radiated from the burning goods and from the walls of the arch, because of its peculiar shape and angle, supplies the necessary heat for complete combustion of the heat units contained in the fuel with which burning is being effected. With my invention, the old method of regenerating the gas by switching it from one flue containing a checker-brick-work to another flue, or, from a supply of hot air induced or supplied from any source to assist combustion, is entirely obviated by the use of the arch and the parallel combustion chamber. I have found from practical experience that a fixed length of combustion chamber prevents any wastage of heat units, as they are entirely consumed, which might not be the case were the combustion chamber either too long or too short. The length of the combustion chamber is determined, for practical results, by the size of the tunnel used in the kiln and in the tonnage of the goods contained on the cars therein.

In connection with my invention, I call attention to the fact that the wares approaching the firing zone have almost reached the temperature of the zone before entering it. Further, that the heat the wares have absorbed is pitted against the heat from the arch which has also absorbed the greatest heat in the combustion chamber, and that each of the two plays its part in supplying, and in filling, the combustion chamber with that intense white heat which compels the consumption of almost every heat unit before it can travel from one end of the combustion chamber to the other end thereof, at which point the greater volume of temperature is finding its way in and around the wares in the tunnel and on down through the kiln, feeding the goods with its temperature until almost entirely consumed before reaching the stack of the kiln.

The constructions and method of operation disclosed, but not claimed, herein are claimed in an application Serial No. 237,166, filed May 28, 1918, and in Serial No. 249,827, filed August 14, 1918.

What I claim is:

60 1. A tunnel kiln having a combustion chamber communicating at its side with the interior of the tunnel and provided with means for deflecting from said chamber into the tunnel the heat and products of combustion developed within said chamber, and

means for firing said combustion chamber in the direction of its length.

2. A tunnel kiln having a combustion chamber communicating with the interior of the tunnel by a relatively large opening 70 and provided with means for directly laterally deflecting and radiating into the tunnel through said opening the heat and products of combustion.

3. The method of firing a tunnel kiln, 75 consisting in developing combustion within a chamber in the general direction of the length thereof, while laterally deflecting and radiating from the chamber into the tunnel the heat and products of combustion.

4. A tunnel kiln having combustion chambers extending along its sides, means for firing said combustion chambers in a direction substantially parallel to the length of the tunnel, and an arch constituting the top 85 of the firing or burning zone of the tunnel, the end portions of said arch constituting the outermost walls of the said combustion chambers.

5. A tunnel kiln having a combustion 90 chamber in communication with the interior of the tunnel and provided with an arch which faces the tunnel and said communication, said arch and communication being so arranged that the arch is adapted to effectually directly deflect and radiate the heat and products of combustion from said chamber through said communication into said tunnel.

6. The method of firing a tunnel kiln, 100 consisting in developing combustion in the general direction of the length of the tunnel of the kiln in a combustion chamber exteriorly of the tunnel while deflecting and radiating laterally into the interior of the 105 tunnel the heat derived from such combustion.

7. A tunnel kiln having a combustion chamber having communication with the interior of the tunnel, means for firing said 110 combustion chamber in the direction of its length and crosswise in relation to the communication aforesaid whereby combustion may be developed in the combustion chamber before passage of the heat and products 115 thereof through said communication, and an arch arranged crosswise of said combustion chamber, said arch facing the tunnel and said communication and being so arranged as to directly deflect and radiate 120 the heat and products of combustion from said chamber through said communication into said tunnel.

8. A tunnel kiln provided with combustion chambers having communication with 125 the tunnel at the opposite sides of the latter, and an arch which comprises outer walls of the combustion chambers and the crown of the tunnel of the kiln, said arch facing the tunnel and said communications and 130

being so arranged as to directly deflect and radiate the heat and products of combustion from said chamber through said communications into said tunnel.

5. 9. A tunnel kiln having a combustion chamber in communication with the tunnel, and an unbroken arch which springs from the floor of the combustion chamber and faces the tunnel, said arch and communication being so arranged that the arch is adapted to laterally deflect and radiate from the chamber into the tunnel the heat and products of combustion.

10. 10. A tunnel kiln having combustion chambers communicating with the tunnel at opposite sides thereof, and an arch which springs from the floors of the respective chambers and comprises the outer walls thereof and the crown of the tunnel of the 15 kiln, said arch being adapted to laterally deflect and radiate from the chambers into the tunnel the heat and products of combustion.

11. 11. A tunnel kiln having a combustion chamber provided with an arch for radiating heat and reflecting products of combustion into the tunnel, and means for baffling the heat and products of combustion to initially direct them in a general downward 20 direction into the tunnel.

12. 12. A tunnel kiln having a combustion chamber provided with an arch for radiat-

ing heat and reflecting the products of combustion into the tunnel, and a baffle extending downward from said arch for causing 35 the radiated heat and reflected products of combustion to be initially directed in a general downward direction into the tunnel.

13. A tunnel kiln having combustion chambers communicating with the tunnel 40 at its sides, an arch which comprises outer walls of the combustion chambers and the crown of the tunnel of the kiln, and means for causing the heat radiated from the arched outer walls of the combustion chambers 45 and the products of combustion reflected by said walls to be initially directed in a general downward direction into the tunnel.

14. A tunnel kiln having combustion 50 chambers communicating with the tunnel at its sides, an arch which comprises outer walls of the combustion chambers and the crown of the tunnel of the kiln, and baffles for the combustion chambers extending 55 downward from said arch which cause the heat radiated from the arched outer walls of the combustion chambers and the products of combustion reflected by said walls to be initially directed in a general downward 60 direction into the tunnel.

In testimony whereof I affix my signature.

JOHN B. OWENS.
